UNITED STATES PATENT OFFICE.

EDWARD KENER, JR., OF BUFFALO, NEW YORK, ASSIGNOR TO BUFFALO CO-OPERATIVE STOVE CO., OF BUFFALO, NEW YORK, A CORPORATION OF NEW YORK.

REFUSE-INCINERATOR.

1,263,432.

Specification of Letters Patent. Patented Apr. 23, 1918.

Application filed February 10, 1915. Serial No. 7,269.

To all whom it may concern:

Be it known that I, EDWARD KENER, Jr., of Buffalo, in the county of Erie and State of New York, have invented new and useful 5 Improvements in Refuse - Incinerators, of which the following is a specification.

This invention relates to an incinerator or a crematory which is more particularly designed for burning or destroying garbage 10 or refuse from the kitchens of households, restaurants, hotels, hospitals, etc., a device of this character being shown in my co-pending application Serial #826,613.

The present invention is an improvement 15 in this type of incinerators and has for one of its objects the provision of improved means for increasing or intensifying the combustion of the gases and smoke developed during the drying and burning of the 20 refuse in order to thoroughly deodorize fumes escaping therefrom.

Another object of my invention is to so construct some of the burners and the grate that they may be agitated from the outside 25 in order to free them of the refuse and to make it possible to break up the mass of refuse as it is being consumed, and also to dump the residue if desired.

In the accompanying drawings:

30 Figure 1 is a front elevation of the incinerator, embodying my invention. Fig. 2 is a transverse vertical section thereof taken in lines 2—2, Fig. 1. Figs. 3 and 4 are horizontal sections taken in lines 3—3 and 4—4, 35 respectively, Fig. 2. Fig. 5 is a vertical section taken in line 5—5, Fig. 2, showing the cones in elevation. Fig. 6 is a vertical section through the burners taken in line 6—6, Fig. 2. Fig. 7 is a transverse vertical section taken in line 7—7, Fig. 4, showing one 40 of the side burners in elevation. Fig. 8 is a sectional elevation similar to Fig. 5 showing a modified construction of the burner.

Similar characters of reference indicate 45 corresponding parts throughout the several views.

1 represents the hollow base of the incinerator which is preferably supported on legs 2 to permit air to reach the underside of the 50 base. Above this base is arranged the ash

pit or box 4 which receives the ashes resulting from the combustion of the garbage or refuse and above the ash pit is arranged the chamber, receptacle or compartment 5 which receives the refuse or garbage to be cremated 55 and which has an outer wall 6.

3 represents the door or lid which controls an opening in the front side of the ash pit 4 for permitting the removal of the ashes from the pit and also to admit air to the furnace and the material under treatment. Above the refuse receptacle is located the outlet or combustion chamber 7 which receives the smoke and combustible vapors or gases given off by the refuse during the 65 process of incineration which products are carried off to a chimney leading to the outer atmosphere by means of a smoke pipe 8 communicating with the top of the outlet chamber 7.

Around the refuse receptacle is arranged a vertical by-pass, flue or passage 10 which has an outer wall 11 and which communicates at its lower end with the ash pit and at its upper end with the upper end of the refuse receptacle and the outlet chamber and also communicates with the lower part of the refuse receptacle by means of a plurality of openings 12 formed in the lower part of the refuse receptacle.

The refuse or garbage to be destroyed or reduced is introduced into the upper part of the refuse receptacle through an inlet chute or spout 13 which opens horizontally into the upper part of the refuse receptacle and is provided at its outer end with a lid or door 14 whereby the same may be opened and closed, as shown in Fig. 1.

At the lower end of the refuse receptacle is arranged a pair of grate sections or supports 15 for the material which is to be incinerated. The central portions of these grate sections are substantially cone-shaped and extend upwardly forming spreading cones 16 which operate to spread the material thrown into the refuse receptacle and prevent the same from packing, so that all parts of the material are exposed to the heating, drying and burning action of the fuel and quick and thorough consumption 100

of the same and reduction thereof to ashes is effected. These grate sections preferably rest upon burners or hollow shafts 17 journaled in bearings on the side walls of the incinerator, being held against lateral displacement thereon by lugs 18 projecting upwardly from each burner shaft and entering suitable notches 19 in the companion grate. In practice it has been found that the refuse while being dried out previous to burning is inclined to cake and carbonize on the upper surface making it difficult for the blaze to penetrate the mass to be consumed. To overcome this the shafts 17 which carry the grate sections are agitated or rocked by a shaker handle 20 mounted thereon so as to be compelled to turn therewith but capable of swinging lengthwise of said shaft for engaging or disengaging said handle with a notched lug 23 on the adjacent outer wall 55 of the incinerator. The pivotal connection between this handle preferably consists in providing the lower end of said handle with a slot and which receives a lug 22 extending upwardly from the burner shaft and is pivoted thereto by a pin 21. The lower end of the notched portion of the shaker handle is constructed to bear against the burner and limit its forward movement, while lugs 23 secured to the wall section act to hold the handle in a vertical position when not in use. Thus by occasionally agitating the grates the mass is broken up allowing the flames to penetrate the mass more readily.

By agitating the mass of refuse that part of the same lying next to the grate which is completely reduced to ashes is discharged into the ash pit to make room for additional fresh refuse at the top of the mass.

If desired the grate sections and spreading cones may be so constructed that they can be completely reversed for dumping the load resting on the grate into the ash pit. Such a construction is shown in Fig. 8 and comprises a plurality of burner shafts 17^a journaled side by side and each supporting a grate section 18^a and a spreading cone 16^a so that the latter may be either turned upwardly into an operative position, as shown by full lines in Fig. 8, or the same may be turned into a pendant position for dumping the grate, as shown by dotted lines in the same figure. Each spreading cone is provided with a plurality of perforations 24, as shown in Figs. 6 and 7.

Between the two shaking spreading cones is arranged a stationary spreading cone 25 which tapers upwardly extending well above the side cones. This central spreading cone is preferably made up of two sections which are provided at their meeting edges with corresponding pairs of coupling lugs 26, while the upper end thereof is

provided with a cap 27 secured thereto by a bolt 28 passing through the cone sections. This cap acts to prevent dirt and the like from getting in between the sections when expanded due to the intense heat and clogging up the burner. The rear base portion of this spreading cone is provided with laterally projecting lugs 29 adapted to be received in a slotted projection 30 extending inwardly from the wall 6 of the refuse chamber. 31 indicates a supporting bracket extending downwardly from the base of the center spreading cone and adapted to encircle a stationary burner 31 holding the center cone centrally with respect to the stationary burner. The front portion of the center cone is also provided with downwardly projecting feet 32 which rest upon lugs 33 projecting laterally from the burner. This center spreading cone and cap are also provided with perforations 34 which act to shoot the flames horizontally across the upper portion of the refuse chamber so as to intercept any gases passing from the refuse while being dried and burned.

Each of the burners preferably consists of a tube extending horizontally across the incinerator having inlets 35, 35^a at the front and rear ends respectively, and outlets 36, 36^a in the central portion thereof, the latter being separated by a partition 36^b.

The outlet 36 of each burner serves to deliver gas into the lower end of the companion spreading cone and communicates with the front gas inlet section 35 of the burner pipe through which the gas is supplied and the other outlet 36^a opens downwardly toward the ash pit and delivers air to the gas issuing from the outlet 36, this air being supplied to the outlet 36^a by the rear air inlet section 35^a with which it communicates and which opens at its rear end to the outer atmosphere. By this means an auxiliary air supply for each burner is provided directly from the exterior of the apparatus in addition to the supply of air received from the ash pit, thereby insuring the maximum heating effect from the gas for promoting incineration of the refuse.

37 represents a main gas supply pipe having a plurality of regulating valves 38 each of which is provided with a conical nozzle 39 which projects in the inlet 35 of one of the burners, thereby forming an air mixing device. This nozzle has a screw connection with the regulating valve so that the distance between the nozzle may be varied to permit more or less air to pass between these members and become mixed with the gas.

Upon throwing a batch of garbage or refuse into the refuse receptacle the spreading cones operate to break the same up more or less in such manner that the mass bridges

the space between the several spreading cones, thereby thoroughly exposing all parts of the refuse to the heating and burning action of the flames and causing the same to be quickly dried and reduced to ashes. The heat of the flames for this purpose passes partly from the burners outwardly through the perforations in the cones of the side burners to the underside of the material also upwardly through the center cone and outwardly therefrom through its perforations and over the material, and also partly inward through the perforation in the side wall of the refuse chamber. From the latter the flames and heated air pass inwardly through the openings 12 in the lower part of the refuse receptacle and also over the upper edge of this receptacle into the interior thereof.

Those gases which are generated or developed from the garbage itself while the latter is being dried, heated and burned more or less by the fuel flames is put into still better combustible condition as it passes into the uppermost chamber 7 by the addition thereto of air which is supplied thereto by a circular air chamber 40 centrally located in said chamber and provided with peripheral openings 41 and is connected to the outside atmosphere by a duct 42 leading to the front wall of the incinerator. This air supply is further augmented by means of an upright air passage 43 arranged outside of the passage and communicating at its lower end by openings 44 in the base with the external atmosphere and by openings 45 in the wall 11 with the chamber 7. By this means air is drawn from the space below the base, carried upwardly through the passage 43 and delivered through the openings 45 into the chamber 7 where it unites with air entering through the openings 41 and mixes with the gases rising from the material undergoing incineration, whereby any combustible elements in these gases are consumed and any odors contained therein are destroyed before the gases escape to the outer atmosphere.

As the fresh air from the external atmosphere passes upwardly through the passage 43 to the combustion chamber 7 the air is not only heated preliminarily to entering the combustion chamber 7 and is therefore in better condition for admixture with the inflammable gases or vapors therein, but this air passing through the passage 43 also forms a heat insulating jacket which aids in preventing radiation of heat from the incinerator to the surrounding space. By thus putting the inflammable gases or vapors which are generated from the refuse or garbage in a final combustible condition in the chamber 7, the consumption or incineration of the garbage or refuse is com-

pleted in this chamber and rendered practically odorless.

In order to prevent the air which passes upwardly through the by-pass 10 from escaping directly through the outlet or combustion chamber 7 to the smoke pipe, an outer baffle or deflector 46, preferably of annular form, is arranged to extend from the inner side of the by-pass wall 11 inwardly over the upper edge of the refuse receptacle wall 6, as shown in Fig. 2, whereby this air is deflected inwardly into the upper part of the refuse receptacle so that it becomes mixed with the inflammable vapors or gases generated by the decomposition of the refuse.

In order to prevent the vapors generated in the refuse receptacle from passing directly upward through the chamber 7 and out through the smoke pipe a central baffle or deflector 47, preferably of circular and downwardly dished form, is arranged between the upper end of the refuse receptacle and the lower side of the chamber 7. The central baffle is provided with perforations 48 to enable the gases and smoke developed from the garbage while the latter is being dried, heated and burned by the fuel flames to readily pass into the chamber 7 where the gases and smoke are mixed with the fresh air and are put in a combustible condition so that they are entirely consumed, thus rendering the incineration odorless. During the operation of this incinerator the baffle or deflector 47 becomes red hot by the action of the flames issuing from the central spreading cone before the refuse has become dried out to any extent, so that this baffle will ignite any combustible gases coming in contact with the same and render the same practically inert and free from odor before escaping to the outer atmosphere. The central deflector or baffle is preferably removably supported at its rear edge upon lugs 49 projecting inwardly from the wall 11 and at its front by a lug 50 projecting outwardly from the baffle and resting on the shelf 51 formed by the bottom of the combustion chamber 7.

52, 53 indicate additional air jackets formed respectively between the outer wall of the air passage and an intermediate wall 54 and between the latter and an outer wall 55 which serve to prevent the incinerator or crematory from unduly heating the space immediately surrounding the same and thereby rendering its presence in a kitchen unobjectionable.

If desired a pilot light 17^b may be provided for lighting either one or all of the burners preparatory to starting incineration.

This incinerator or crematory is comparatively simple and inexpensive in construction, and is so constructed as to completely incinerate the garbage without discharging any odor. Furthermore, it is of such a con-

struction that the gases developed during the consumption of the refuse is utilized as part of the heating agent, thereby rendering the operation of the apparatus comparatively inexpensive.

5 I claim as my invention:

- 10 1. A refuse incinerator comprising a refuse receptacle having a perforated wall, an ash pit arranged below said receptacle, perforated cones arranged in said receptacle, burners arranged below said cones and adapted to deliver flames into the respective cones, an upright flue surrounding said receptacle and communicating at its lower end with said ash pit, a combustion chamber communicating with the upper ends of said receptacle and said flue, an outer deflector projecting from the wall of said chamber inwardly over the upper end of the wall of 15 said receptacle, and an annular air passage surrounding said flue and receptacle connecting at its lower end with the outer atmosphere and at its upper end with the combustion chamber.
- 20 2. A refuse incinerator comprising a refuse receptacle having a perforated wall, an ash pit arranged below said receptacle, perforated cones arranged in said receptacle, burners arranged below said cones and adapted to deliver flames into the respective cones, an upright flue surrounding said receptacle and communicating at its lower end with said ash pit, a combustion chamber communicating with the upper end of said receptacle and said flue, an outer deflector projecting from the wall of said combustion chamber inwardly over the upper end of the wall of 25 said receptacle, an inner perforated deflector arranged between the upper end of said receptacle and the lower end of said combustion chamber and projecting outwardly over said outer deflector, and an annular air passage surrounding said flue and receptacle connecting at its lower end with the outer atmosphere and at its upper end with the combustion chamber.
- 30 3. A refuse incinerator comprising a refuse chamber, a combustion chamber arranged above said refuse chamber and provided with an outlet and an inlet for air communicating directly with the outer atmosphere, a perforated baffle arranged between said refuse chamber and said combustion chamber, a perforated cone arranged centrally within the refuse chamber below said perforated baffle, and means for feeding gas and air to the interior of said cone and producing a flame within the latter.
- 35 4. A refuse incinerator comprising a refuse chamber, a plurality of perforated spreading cones arranged in the lower part of said chamber, burners arranged below said chamber and supporting said cones and adapted to deliver flames into the respective

cones, the outer burners adapted to be oscillated.

5. A refuse incinerator comprising a refuse chamber, a stationary perforated spreading cone arranged centrally therein, a burner arranged below said chamber under said cone, rocking grate cones arranged on either side of said stationary cone, and rocking burners arranged below said chamber and supporting said rocking grate and adapted to deliver flames into the respective cones.

6. A refuse incinerator comprising a refuse chamber, a stationary perforated spreading cone arranged centrally therein, a stationary burner arranged below said chamber and supporting said cone, rocking grate cones arranged on either side of said stationary cone, and rocking burners arranged below said chamber and supporting said rocking grate cones and adapted to deliver flames into the respective cones.

7. A refuse incinerator comprising a refuse chamber, a stationary perforated cone arranged centrally at the lower end thereof and extending up into said chamber, a burner arranged below said cone and supporting the front end thereof, the rear of said cone being supported in the wall of said chamber, rocking grate cones arranged on either side of said stationary burner, and rocking burners arranged below said rocking grate and supporting said rocking grate cones and adapted to deliver flames into the respective cones.

8. A refuse incinerator comprising a refuse chamber, a stationary perforated spreading cone arranged centrally therein, a burner arranged below said chamber and under said cone and adapted to deliver a flame into said cone, rocking burners arranged on either side of said stationary cone extending to the outside of the incinerator, grate cones mounted thereon, rocking levers arranged on the outside end of said burners.

9. A refuse incinerator comprising a refuse receptacle, a burner arranged below said receptacle and having a fuel supply pipe, a valve arranged in said pipe for controlling the passage of fuel to said burner at the front end thereof, and an air inlet extending from the rear of said burner to the center thereof independent of said fuel supply end.

10. A refuse incinerator comprising a refuse receptacle, a stationary perforated spreading cone arranged centrally therein, a burner arranged below said receptacle under said cone and adapted to deliver a flame into said cone, rocking grate cones arranged on either side of said stationary cone, rocking burners supporting said grate cones, an ash pit arranged below the refuse receptacle, a flue arranged adjacent to the outer side of

said receptacle and communicating at its lower end with said ash pit, a combustion chamber communicating with the upper ends of said receptacle and flue, a smoke outlet flue communicating with the combustion chamber, an annular air passage surrounding said flue and receptacle and connecting at its lower end with the outer atmosphere, and at its upper end with the combustion chamber, and an additional air inlet extending from the outer atmosphere to the central part of the combustion chamber.

Witness my hand this 8th day of February, 1915.
